MATRIX FOR TYPOGRAPHICAL MACHINES

Alfred W. F. Guest, Brooklyn, N. Y., assignor to
Mergenthaler Linotype Company, a corpora-
tion of New York

Application November 18, 1932
Serial No. 643,141

15 Claims. (Cl. 199—63)

This invention relates to slug casting machines, such as linotype machines of the general organization represented in United States Letters Patent No. 436,532 to O. Mergenthaler, wherein circulating matrices are released from a magazine in the order in which their characters are to appear in print and then assembled in line, the composed line transferred to the face of a slotted mold, the mold filled with molten metal to form a slug or linotype against the matrices which produce the type characters thereon, and the matrices thereafter returned through a distributing mechanism to the magazine from which they started.

15 It has been found, in the case of quadded slugs, that the height of the type characters above the top edge or quad line of the slug body is insufficient to prevent the quadded portion of the slug from being inked during printing and producing 20 a smear on the printed paper. According to the prior art, matrices for effecting a low quad have been formed on their casting edges each with a projection adapted to extend into the mold slot, but such matrices have been found to be impracticable due to the peculiar operation of a 25 slug casting machine wherein the alinement of the type forming matrices with the mold slot is effected by an upward movement of the line transporter or first elevator which brings the 30 lower ears of the matrices up against an alining rib on the front face of the mold. When such low quad matrices are used, the first elevator is prevented from rising to effect alinement.

The object of the present invention is to obviate this objectionable feature and to provide 35 a matrix which will effect the desired low quadding without interfering with the proper alinement of the type forming matrices with the mold slot. To that end, the invention contemplates 40 a special form of blank or quad matrix in which the low quad element (that enters the mold slot) is mounted so as to permit of a relative movement between it and the body portion of the matrix.

45 In the accompanying drawing, the invention has been shown merely by way of example and in preferred form, and obviously many variations and modifications may be made therein without departing from the spirit of the invention. It is 50 to be understood, therefore, that the invention is not limited to any specific form or embodiment, except insofar as such limitations are specified in the appended claims.

Referring to the drawing:

55 Fig. 1 is a vertical section through the mold

and first elevator, showing as presented to the mold in unaligned condition, a line of matrices which includes one or more of the improved quad matrices, certain of the parts being broken away to illustrate the cooperation of the low quad element with the mold; 60

Fig. 2 is an enlarged view similar to Fig. 1, showing the relation of the quad matrix to the mold in the aligned condition of the composed line; 65

Fig. 3 is a front elevation of the casting edge of the quad matrix;

Fig. 4 is a side elevation of the quad matrix, partly broken away to show the interior construction; 70

Fig. 5 is a transverse section taken on the line 5—5 of Fig. 4, looking in the direction of the arrow; and

Fig. 6 is a perspective view of a slug produced by a line made of regular and quad matrices. 75

In the operation of the ordinary linotype machine, a composed line (with or without blanks or quads) of standard type producing matrices M is delivered to a line transporter or first elevator B, which then presents the line to a slotted mold C carried by a rotatable mold disc D. The mold C shown is made up of a cap portion c and a body portion c', which define between them a mold slot or cavity c² in which the slug or linotype S is cast. To the front face of the body portion c' of the mold, there is secured an alining plate E formed with superposed continuous longitudinal grooves e, in which the lower ears m on the rear edges of the matrices enter when the latter are positioned before the mold, it being understood that the matrices may be composed in the line at an upper or lower lever as desired. After the line has thus been presented to the mold, the line transporter B is raised slightly to bring all of the ears m of the matrices into engagement with an alining rib e' formed on the plate E or an alining rib c³ formed directly on the mold, as the case may be. 85

As before stated, it is the object of the present invention to provide a low quad matrix which will permit the upward movement of the first elevator in effecting the alinement of the matrices with the mold slot. This quad matrix A comprises, like a regular matrix M, a body portion A' of the usual rectangular shape and provided at its four corners with projecting ears A², and which is formed at the top with a V-shaped notch A³ having distributing teeth A⁴ formed on its convergent walls. 90

The body portion A' of the quad matrix A is 100

105

110

formed on its casting edge with a shallow recess A⁵ which extends through the body from one side to the other. Leading from the recess A⁵ is a second deeper but narrower recess A⁶ fully contained within the body A' of the matrix. These recesses A⁵ and A⁶ are adapted to receive a casting member a presenting a head portion a' which fills the recess A⁵ except for a small clearance space a² at the bottom and a stem portion a³ which fits snugly in the recess A⁶ except for a small clearance space a⁴ at the bottom. The clearance spaces a² and a⁴ are provided to enable the casting member to partake of a slight relative movement with respect to the body portion A', the extent of such movement being approximately the same or slightly greater than that of the first elevator in effecting the alinement of the matrices with the mold slot. The stem portion a³ is formed near its upper end with a slot a⁵ through which passes a pin a⁶ anchored in the body portion A' of the matrix A. This pin and slot connection retains the casting member in the recesses A⁵ and A⁶, yet permits of a relative vertical movement between the casting member a and the matrix body A'. At its lower end, the stem portion a³ is formed with a vertical recess a⁷ in which a compression spring a⁸ is arranged, the spring projecting from the recess and bearing against the lower wall A⁷ of the recess A⁶ under sufficient pressure normally to maintain the casting member in its uppermost position, as illustrated in Fig. 4.

As will be observed, the front or casting face of the head portion a' is flush with the casting edge of the matrix body A' except for the presence on the head portion of a quad element a⁹ which is adapted to enter the mold slot c². This quad element will of course vary in height and width according to the matrix font in use. In the example illustrated, the quad matrix is one of the larger varieties, the quad element a⁹ having a set width in thickness of 3 ems and a point size in height of, say, 36 point. Of course, as just stated, these dimensions may be varied to suit different conditions. When the quad matrix is to be machine-composed and circulated through the machine with the regular matrices, naturally the dimensions of the quad element will be more or less limited,—more so as to set width than as to point size. When, however, the quad matrix is not required to be machine-composed or circulated through the machine, the dimensions of the quad element are practically unlimited, although in any case the main utility of the quad matrix will be present when it is composed in line with type producing matrices which are alined with the mold by a relative movement of the mold and the line transporter.

When a line of matrices composed of regular type producing matrices M and one or more of the improved quad matrices A is delivered to the first elevator B, which thereafter descends until arrested at the proper casting level by a stop F located on top of the vise frame G in which the first elevator B is slidably mounted, the mold disc D carrying the mold C occupies its retracted position. Immediately after the line of matrices is presented to casting position, the disc D advances to bring the mold C into casting relation with the line of matrices. It is during this forward movement of the mold disc D and mold C that the quadding element a⁹ enters the mold slot c², and the ears m and A² of the regular and quadding matrices, respectively, enter the alining groove e. Immediately

thereafter, the first elevator B rises slightly to effect the alinement of the line of matrices with the mold slot c². Due to the engagement of the quadding element a⁹ in the mold slot c², the casting member a is held against vertical movement, but because of the relative movement permitted between the casting element a and the matrix body A', the latter is free to be moved upwardly against the pressure of the spring a⁸ when the alinement of the line of matrices with the mold slot is effected.

In Fig. 6, there is illustrated a slug S cast from a line composed of the regular type producing matrices M and a plurality of the improved quad matrices A. The slug is of the ordinary recessed variety comprising a body portion S' and an overhanging character bearing portion S² supported by transverse ribs S³. It will be noted that the characters s formed on the overhanging portion S² by the intaglio characters of the regular matrices M all rise for a considerable height above the blank portion s² formed by the projection of the quad elements a⁹ into the mold slot, and this portion s² of the slug S is therefore sufficiently low to escape being inked and smearing the paper during printing.

While the foregoing description deals specifically with a low quad matrix adapted to be used in conjunction with regular type producing matrices, the invention comprehends any form of matrix having a projection adapted to enter the mold, whether for the purpose described or any other purpose.

Having thus described my invention, what I claim is:

1. A matrix for use in slug casting machines, comprising a body portion provided on its casting edge with a relatively movable mold entering element.
2. A matrix for use in slug casting machines, comprising a body portion provided on its casting edge with a mold entering element mounted for vertical movement relative to the body portion.
3. A matrix for use in slug casting machines, comprising a body portion formed in one edge with a recess and having a casting member movably mounted in said recess and formed with a mold entering element.
4. A matrix for use in slug casting machines, comprising a body portion formed in one edge with a recess and having a casting member movably mounted in said recess and formed with a mold entering element, said casting member normally occupying a definite position in said recess and being movable from said normal position.
5. A matrix for use in slug casting machines, comprising a body portion formed in one edge with a recess, a casting member movably mounted in said recess and formed with a mold entering element, and spring means acting to maintain said casting member normally in a definite position in said recess and to permit of a relative movement between the casting member and the body portion.
6. A matrix for use in slug casting machines, comprising a body portion formed in one edge with a recess, a casting member formed with a head portion and a stem portion and adapted to fit in said recess with the front face of the head portion flush with the casting edge of the matrix, a mold entering element formed on said head portion, a slot formed in said stem portion and adapted to receive a retaining pin anchored in the matrix body, and a compression spring ar-

ranged between the casting member and the matrix body for maintaining the casting member in normal position and to permit of a relative movement between the casting member and the matrix body.

5 7. A matrix as described in claim 6, wherein the spring seats in a recess formed in the stem portion of the casting member and projects therefrom to bear against the lower wall of the 10 recess in the matrix body in which the casting member is fitted.

15 8. A matrix as described in claim 6, wherein the head portion of the casting member seats in a shallow recess formed on the casting edge of the matrix body and extending through the body from one side to the other, and the stem portion seats in a deeper recess leading from said shallow recess and fully contained within the matrix body.

20 9. A matrix as described in claim 6, wherein the head portion of the casting member seats in a shallow recess formed on the casting edge of the matrix body and extending through the body from one side to the other, and the stem portion 25 seats in a deeper recess leading from said shallow recess and fully contained within the matrix body, said head portion having its front face flush with the casting edge of the matrix body and being formed with a mold entering element projecting therefrom.

30 10. A matrix as described in claim 6, wherein the head portion of the casting member seats in a shallow recess formed on the casting edge of the matrix body and extending through the body 35 from one side to the other, and the stem portion seats in a deeper recess leading from said shallow recess and fully contained within the matrix body, said head and stem portions filling their respective containing recesses except for a clearance space to permit of a relative vertical movement 40 between the casting member and the matrix body.

45 11. A matrix as described in claim 6, characterized by the fact that the casting member is of less height than the height of the recess in which it is fitted and that the difference between these two heights determines the amount of relative movement permitted between the casting member and the matrix body.

50 12. A matrix for use in slug casting machines comprising a body portion formed in one edge with a recess, a casting member comprising a head portion and a stem portion and being mounted in said recess for movement relative to the matrix body, a slot formed transversely through

the stem portion and through which a pin anchored in the matrix body passes to retain the casting member in the recess, and a spring fitted in a recess formed in the lower edge of the stem portion, said spring being adapted to project 80 from the recess in which it is fitted and bear against the lower wall defining the recess in the matrix body with sufficient pressure to maintain the casting member in normal position, and being compressible to permit of a relative movement 85 between the casting member and the matrix body.

13. In or for a slug casting machine, the combination of a slotted mold, a line of matrices including one or more matrices having each a body portion formed with a mold entering element, and a movable transporter for presenting and alining the line of matrices with the mold slot, said mold entering element being movable with respect to the body portion of the matrix to permit the movement of the transporter in effecting 95 alinement.

14. In or for a slug casting machine, the combination of a slotted mold, a line of matrices including one or more matrices having each a body portion provided with a relatively movable 100 casting member formed with a mold entering element, and a movable transporter for presenting the line of matrices to the mold for casting and thereafter moving the line of matrices bodily to effect their alinement with the mold slot, the 105 relative movement of the casting member and the matrix body permitting the movement of the transporter after the mold entering element has engaged with the mold slot.

15. In or for a slug casting machine, the combination of a slotted mold, a line of matrices adapted to cooperate with the mold for casting a slug, and a vertically movable transporter for presenting the line to the mold and alining the matrices with the mold slot by a slight upward 110 movement, said line including one or more matrices having a body portion provided with a relatively movable casting member formed with a mold entering element, and means for holding 115 said casting member in normal position to enter the mold slot before alinement of the line of matrices is effected, said holding means being yieldable to permit of a relative movement between the casting member and the matrix body, whereby when the mold entering element is engaged in the mold slot the transporter will be 120 permitted to raise the line of matrices to effect alinement.
